CLAIM

The ornamental design for a display screen with graphical user interface, as shown and described.

DESCRIPTION

FIG. 1 is a front view of a first embodiment for a display screen with graphical user interface; and, FIG. 2 is a front view of a second embodiment for a display screen with graphical user interface.

The broken line showing of an electronic device and display screen is for the purpose of illustrating environmental structure, and forms no part of the claimed design. The remaining broken lines illustrate portions of the graphical user interface that form no part of the claimed design.

1 Claim, 2 Drawing Sheets
